(57) **CLAIM**

The ornamental design for a child-resistant cabinet latch, as shown and described.

DESCRIPTION

FIG. 1 is a right side elevational view of the child-resistant cabinet latch, showing my new design. The left side elevational view is a mirror image thereof.

FIG. 2 is an isometric view thereof, taken from the front upper right.

FIG. 3 is an isometric view thereof, taken from the front lower left.

FIG. 4 is an isometric view thereof, taken from the left upper rear.

The drawings show surface shading rather than surface ornamentation.
